Inventor:
Bernarr Macfadden,
By his Atty, J. H. Richards.

UNITED STATES PATENT OFFICE.

BERNARR MACFADDEN, OF NEW YORK, N. Y.

SPINE-EXERCISER.

1,336,910.

Specification of Letters Patent. Patented Apr. 13, 1920.

Application filed March 22, 1919. Serial No. 284,381.

To all whom it may concern:

Be it known that I, BERNARR MACFADDEN, a citizen of the United States, residing in New York city, in the county of New York 5 and State of New York, have invented certain new and useful Improvements in Spine-Exercisers, of which the following is a specification.

This invention relates to devices for exercising and stretching the spine, and has for 10 its object to provide a device of this kind which may be economically manufactured, which may be easily used without having it permanently secured to anything, and which 15 may be suitably adjusted to different persons. It is understood that many changes may be made in its structure without departing from the scope of the invention as claimed.

20 In the accompanying drawing,

Figure 1 is a perspective view showing the improved devices worn and used by a person lying on an ordinary bed;

Fig. 2 is a perspective view showing the 25 details of construction of the head piece of the exercising devices; and

Fig. 3 is a perspective view of the foot piece.

The invention comprises a head piece 5, 30 adapted to be worn upon the head of the user or patient, and a foot strap 6, adapted to receive the ankles of the patient lying on an ordinary bed 7 as shown in Fig. 1. The head piece comprises a neck band 8 35 provided at the front with a buckle 9, for adjusting the strap about the head of the user, in which case a towel 10 may be placed around the neck for comfort. The head piece also comprises a pair of crossed straps 40 11, stitched together at the intersection by stitches 12, and having their rear ends 13 stitched to either side of the rearmost portion of the neck band. The front ends of the crossed straps are folded and stitched 45 upon themselves as at 15, thereby forming loops 16, loosely receiving the front end portions of the neck band to permit said front ends of the straps to be adjusted on the neck band thereby to make the head piece 50 more comfortable to the user. The exercising rope 18 is passed under said intersection and may then be passed around a head post 20 of the bed, and then held in the hands of the user.

55 The foot piece 6 comprises a single wide flexible strap 22 formed with a tying end 23

adapted to be tied, for instance, to one of the foot posts 24 of the bed. The other end of the foot strap is folded and stitched to itself, thereby forming a loop 25, just large 60 enough to pass the feet through comfortably, and small enough when thus worn to bind itself about the ankle and prevent its passing off over the feet.

The spine exercising device may be used 65 as follows:

After the device has been put on and adjusted upon the user and the foot piece secured to one of the foot posts of the bed, and the exercising ropes passed over the 70 diagonally opposite head post, the user merely grasps the exercising ropes in his hands, as shown in Fig. 1, and drawing them down, thereby stretches himself with such force and duration as seems best, and as 75 many times as he desires.

Many ways of using the device will suggest themselves. For instance, the head piece only may be worn, with the exercising ropes applied while the user is standing 80 near an open door, the exercising ropes being passed over the top of the door, pulley fashion, so that the user by grasping the ropes in his hands may draw himself upwardly, thereby stretching and exercising 85 the spine.

Obviously the ropes may be passed over any convenient device and the foot strap fastened to any suitable object other than the ones mentioned.

90 Many advantages result from the use of this device as will be apparent.

I claim:

1. In a spine exerciser, a head piece comprising a neck band; crossed head straps 95 each having one end secured to the neck band, and its other end loosely secured to portions of the neck band to permit them to be adjusted.

2. In a spine exerciser, a head piece comprising a neck band; and a pair of head straps crossed and stitched together at the intersection and each having its rear end secured to the rear portion of said neck band, and its front end folded and formed 100 into a loop loosely receiving front portions of the neck band to permit said front ends to be adjusted on the neck band.

3. In a spine exerciser, a head piece comprising a neck band provided with a front 110 buckle for adjusting the band to the neck; and a pair of head straps crossed and

stitched together at the intersection and each having its rear end stitched to the rear portion of said neck band, and its front end folded upon and stitched to itself and thus forming a loop loosely receiving the front end portions of the neck band to permit said front ends to be adjusted on the neck band.

4. In a spine exerciser, a head piece comprising a neck band provided with a front 10 buckle for adjusting the band to the neck, and a pair of head straps crossed and stitched together at the intersection and each having its rear end stitched to the rear portion of said neck band, and its front end 15 folded upon and stitched to itself and thus forming a loop loosely receiving the front end portions of the neck band to permit said front ends to be adjusted on the neck band; and an exercising rope passed under said 20 intersection and adapted to be passed over an object pulley-fashion and grasped by the hands.

5. In a spine exerciser, a head piece comprising a neck band provided with a front 25 buckle for adjusting the band to the neck, and a pair of head straps crossed and stitched together at the intersection and each having its rear end stitched to the rear portion of said neck band, and its front end 30 folded upon and stitched to itself and thus forming a loop loosely receiving the front end portions of the neck band to permit said front ends to be adjusted on the neck band; and an exercising rope passed under said 35 intersection and adapted to be passed over an object pulley-fashion and grasped by the hands.

6. In a spine exerciser, the combination of a wide flexible foot strap formed with 40 a tying extension and a single loop through which the feet may be thrust and in which

the ankles may be received and held; a head piece comprising a neck band provided with a front buckle for adjusting the band to the neck, and a pair of head straps crossed and 45 stitched together at the intersection and each having its rear end stitched to the rear portion of said neck band, and its front end folded upon and stitched to itself and thus forming a loop loosely receiving the 50 front end portions of the neck band to permit said front ends to be adjusted on the neck band; and an exercising rope passed under said intersection and adapted to be passed over an object pulley-fashion and 55 grasped by the hands.

7. In combination with a bed on which a person may lie, a spine exerciser comprising a wide flexible foot strap formed with a tying extension adapted to be tied to a foot 60 post of the bed, and a single loop through which the person's feet may be thrust and in which the ankles may be received and held; a head piece having a neck band provided with a front buckle for adjusting the band 65 to the neck, and a pair of head straps crossed at the top of the head and stitched together at the intersection and each having its rear end stitched to the rear portion of said neck band, and its front end folded upon 70 and stitched to itself and thus forming a loop loosely receiving the front end portions of the neck band to permit said front ends to be adjusted on the neck band; and an exercising rope passed under said intersection and passed pulley-fashion over one 75 of the head posts diagonally opposite to said foot post and grasped by the hands.

BERNARR MACFADDEN.
